UNITED STATES PATENT OFFICE.

HOWARD R. SARGENT, OF SCHENECTADY, NEW YORK, ASSIGNOR TO GENERAL ELECTRIC COMPANY, A CORPORATION OF NEW YORK.

ATTACHING-PLUG.

957,261.

Specification of Letters Patent. Patented May 10, 1910.

Application filed October 1, 1907. Serial No. 395,457.

To all whom it may concern:

Be it known that I, HOWARD R. SARGENT, a citizen of the United States, residing at Schenectady, county of Schenectady, State of New York, have invented certain new and useful Improvements in Attaching-Plugs, of which the following is a specification.

This invention relates to devices for making connections in electric circuits, and its object is to simplify the construction and provide greater safeguards against overloads in attaching plugs.

The invention consists, in brief, of a plug having a removable inclosed fuse in each side of the circuit, and a removable cap carrying contacts which coöperate with clips in the body of the plug.

In the accompanying drawing, Figure 1 is a plan view of the body of an attaching plug embodying my invention; Fig. 2 is a longitudinal central section of the entire plug; Fig. 3 is a plan view of the cap; Fig. 4 is a perspective view of one of the contacts on the cap; Fig. 5 is a perspective view of one of the clips in the body of the plug, and Fig. 6 is a perspective view of the diaphragm which covers the fuses.

The body 1, cap 2 and diaphragm 3 are made preferably of molded insulation, such as porcelain. The body has a cylindrical neck 4 provided with a screw-threaded metallic sleeve 5 having an internal flange at its outer end which is clamped by a washer 6 of insulation placed against the end of the neck and secured by a long screw 7 which passes centrally through said neck and engages with a tapped hole in a bar 8 of hard rubber or fiber extending diametrically across a recess, formed in the body 1. A metallic washer 9 is placed under the head of the screw 7. A diaphragm 3 preferably of porcelain, fits easily into the recess in the body and rests upon the bar 8, being secured in place by a screw 10 passing through a central hole 11 in said diaphragm and engaging with a tapped hole in the bar 8, preferably the same hole as that into which the screw 7 enters. The space between the diaphragm and the bottom of the recess is thus divided by the bar 8 into two separate chambers. An inclosed fuse 12, 12' is located in each chamber. The fuses are of the cartridge type and are held at each end in the resilient jaws of a clamp 13, 14, 15, 16 which

allow them to be easily inserted and removed when desired. The clamp 13 in one chamber is suitably connected with the metallic sleeve 5, while the clamp 14 in the other chamber is connected with the central screw 7, the sleeve and screw forming the contacts for connecting said clamps with the terminals of a circuit when the plug is screwed into a line receptacle. The clamps 15, 16 are in line, respectively, with the clamps 13, 14, and each one has a clip 17, 18 extending respectively toward openings 19, 20 in the diaphragm 9. The preferred construction of the clamps 15, 16 and their clips is shown in Fig. 5, where the clamp and clip are seen to be V-shaped pieces of sheet metal with their axes at right angles. An L-shaped metallic plate 21 is laid in the bights of these two pieces and a fastening screw 22 is tapped into said plate, through a hole in the body 1.

The cap 2 has a central hole 23 for the entrance of a conducting cable whose terminals can be secured by binding screws 24 to plates 25 attached to the inside of the cap and having preferably integral contact blades 26, 27 which are adapted, when the cap is put on the body, to pass through the openings 19, 20 and engage with the clips 17, 18, respectively.

The construction is exceedingly compact and symmetrical, and yet affords ample protection against short-circuiting. The double fuse feature gives an especially good protection against overloads, and if a fuse blows it can be readily replaced by an unskilled person.

What I claim as new and desire to secure by Letters Patent of the United States, is:

1. An attaching plug having a recessed body divided into two chambers, a line terminal in each chamber, and a removable inclosed fuse in each chamber.

2. An attaching plug having a recessed body divided into two chambers, a line terminal in each chamber, a removable inclosed fuse in each chamber, and a perforated diaphragm covering said fuses but affording access to said terminals.

3. An attaching plug having a recessed body divided into two chambers, a line terminal in each chamber, a removable inclosed fuse in each chamber, a perforated diaphragm covering said fuses but affording access to said terminals, and a removable cap

carrying branch-line terminals adapted to pass through said diaphragm.

4. An attaching plug having a recessed body, a transverse bar of insulation therein dividing it into two chambers, a pair of clamps in each chamber, a removable inclosed fuse received in each pair of clamps, a clip in each chamber connected with one of said clamps, and a cap carrying contacts 10 to engage with said clips.

5. An attaching plug having a recessed body, a bar of insulation dividing said recess into two chambers, a diaphragm secured to said bar, a pair of clamps in each chamber, an inclosed fuse removably held in each 15 pair of clamps, a clip in each chamber connected with one of said clamps, a cap having a hole for a cable, and contact blades inside

of said cap adapted to pass through said diaphragm and enter said clips.

6. An attachment plug, having on its under side contact terminals and on its upper side a cup-shaped body separated into two chambers by a transverse insulating wall, and two plates in each chamber carrying 25 clips for a horizontal inclosed fuse, one plate in each chamber being connected to one of said terminals, and a cap for the chambered part of the body.

In witness whereof, I have hereunto set 30 my hand this 27th day of September, 1907.

HOWARD R. SARGENT.
